UNITED STATES PATENT OFFICE.

ROBERT SAYER ASPINWALL, OF DETROIT, MICHIGAN.

DESIGN FOR A COMBINED PORCH LANTERN AND SUPPORTING BRACKET.

Application filed July 7, 1928. Serial No 27,414. Term of patent 7 years.

To all whom it may concern:

Be it known that I, ROBERT SAYER ASPINWALL, a citizen of the United States, residing at Detroit, county of Wayne, State of Michigan, have invented a new, original, and ornamental Design for a Combined Porch Lantern and Supporting Bracket, of which the following is a specification, reference being had to the accompanying drawing, forming part thereof.

Fig. 1 is a side elevation.

Fig. 2 is a plan.

I claim:

The ornamental design for a combined porch lantern and supporting bracket, as shown.

ROBERT SAYER ASPINWALL.
